UNITED STATES PATENT OFFICE.

WILLIAM FITZGERALD, OF BRIDGEPORT, CONNECTICUT.

PUZZLE.

1,133,546.

Specification of Letters Patent. Patented Mar. 30, 1915.

Application filed October 24, 1914. Serial No. 868,427.

To all whom it may concern:

Be it known that I, WILLIAM FITZGERALD, a citizen of the United States, residing at Bridgeport, in the county of Fairfield and State of Connecticut, have invented certain new and useful Improvements in Puzzles; and I do hereby declare the following to be a full, clear, and exact description of the invention, such as will enable others skilled in the art to which it appertains to make and use the same.

This invention relates to puzzles and in particular to puzzles of the game board type.

15 One of the objects of this invention is to provide a puzzle which one person can play to a conclusion.

Another object of this invention is to provide a device whereby a game board is so constructed that either marbles, dice, pegs or disks can be used in the operation thereof.

25 A still further object of this invention is to provide a device whereby the moves of the game or puzzle are made exceedingly intricate and difficult by having single corner pockets or openings in the game board with relation to a free central opening.

Still another object of this invention is to provide a device whereby the instruments used can be successively jumped and removed from the board under the rules until there is only one remaining in the central pocket.

Other objects and advantages of this invention will be hereinafter more clearly set forth in the specifications and pointed out in the claims.

Similar characters of reference refer to similar parts in the drawings, in which, 40 Figure 1 is a top plan view of my game board with the openings or pockets shown therein, Fig. 2 is an edge view thereof showing the method of forming the openings or pockets through the game board, and Fig. 3 is a detail of the game board showing the relative position of the corner opening with relation to the balance of the openings.

In the drawings, 1 is my game board composed of paper, wood or metal, as is desirable, but preferably of metal, having stamped therethrough a series of openings or pockets 2, said openings consisting of an upper concavial portion 3 and a lower aper- 55 tured portion 4, the forming of the aper- tured portion 4 making a depressed lower

ring 5 therearound adapted to act as a wall for a peg, thereby forming a deep seat or as a foot to the game board, these depressed portions being formed substantially shown 60 in Fig. 2 of the drawings; the apertured portion 4 of the opening is substantially of less diameter than the diameter of the concavial portion.

The game board is composed of substantially square material having one of the above described openings centrally disposed therethrough, which is one of the fundamental or base openings of the game or puzzle, with a row or line of openings 65 radiating from said central opening to the corners of the game board, the end openings each of which is one of the fundamental or base openings of the game, is positioned approximately within a corner section of 70 the board. There should be a total of nine openings, counting the center opening in each of these radial rows. A pair of parallel rows are had on each side of the above described rows, each opening therein registering with one of the openings of the first mentioned row, but including only seven openings to a row thereby leaving the corner opening previously described isolated. For convenience in operation each one of 75 these openings, beginning with the lower left hand corner and running from left to right as each parallel row is advanced, are numbered from 1 to 37 consecutively, as plainly shown in Fig. 1 of the drawings. A 80 marble, die, disk or other suitable instrument 3' is positioned in each of the pockets with the exception of the central opening numbered 19 as above described.

With the arrangement of the pockets as 85 above described, it is impossible to make the same number and perform as intricate moves as can be made with the above device if the corner pockets are missing; a fundamental change of operations being necessary if a 90 less number of pockets or openings are used; say, for instance, 33.

In the operation of the game the object is to successively jump each one of the instruments, removing the instrument jumped 105 from the board, until the last remaining instrument remains in the central opening, numbered 19 as above described. It takes 35 moves to bring this game or puzzle to a solution, which can be attained by several 110 different operations, each intricate in their several ways but for convenience of illus-

tration the herein solution is given as a means of showing a solution of the puzzle. In this solution, move as follows:—Jump instrument in pocket 17 over 18, 15—16, 5—10, 8—9, 11—10, 7—6, 20—12, 4—7, 1—3, 13—12, 29—21, 2—5, 14—13, 27—28, 36—33, 31—32, 33—28, 30—29, 20—12, 23—22, 7—6, 18—19, 5—10, 18—26, 37—35, 34—31, 21—20, 25—26, 28—27, 11—19, 27—26, 10 24—25, 9—17, 25—26, and 32—27. By this solution it is to be noticed that the last move is 32 over 27 which brings the instrument which was in 32 now in 19, the central opening of the board, ending the game or 15 puzzle as previously described.

Having now described my invention, what I claim as new and desire to secure by Letters Patent, is:—

1. A game board puzzle, comprising, a 20 game board, having a series of thirty-seven openings therein, a portion of said openings being in registering parallel rows, with one

opening in the center and one isolated opening in each of the corners of said game board, consecutively numbered from 1 to 37, 25 and each advancing row reading from left to right starting in the lower left hand corner.

2. A game board puzzle, comprising a game board, having thirty-seven openings therein, thirty-six instruments, one upon each of said openings with the exception of the central opening thereto adapted to be consecutively jumped over each other in thirty-five moves so that the last instrument used will be jumped to the central opening. 30 35

In testimony whereof I have signed my name to this specification in the presence of two subscribing witnesses.

WILLIAM FITZGERALD
